United States Patent Office

Des. 183,328
Patented Aug. 5, 1958

183,328

DINNERWARE

Gerald S. Stone, Scarsdale, N. Y., assignor to Johnson Bros. (Hanley) Limited, Stoke-on-Trent, England, a British company

Application March 31, 1958, Serial No. 50,256

Term of patent 14 years

(Cl. D44—15)

The figure is a top plan view of a plate or similar article of dinnerware of conventional configuration illustrating my new design.

I claim:

The ornamental design for dinnerware, substantially as shown and described.
